MOUNTING FOR ROCK DRILLS

Dudley W. Hart, Phillipsburg, N. J., assignor to
Ingersoll-Rand Company, Jersey City, N. J., a
corporation of New Jersey

Application February 18, 1937, Serial No. 126,412

6 Claims. (Cl. 255—51)

This invention relates to mountings for rock drills, and more particularly to a wheel mounting capable of being readily transported to and from the work.

One object of the invention is to enable the rock drill to be expeditiously and conveniently disposed in position for drilling either vertical or inclined holes.

Other objects will be in part obvious and in part pointed out hereinafter.

In the accompanying drawings and in which similar reference numerals refer to similar parts,

Figure 1 is a front elevation, partly broken away, of a mounting constructed in accordance with the practice of the invention.

Figures 2 and 3 are transverse views taken through Figure 1 on the lines 2—2 and 3—3 looking in the directions indicated by the arrows.

Figure 4 is a side view, in elevation, of the mounting.

Figure 5 is a transverse view taken through Figure 4 on the line 5—5.

Figure 6 is a view taken through Figure 5 on the line 6—6, and

Figure 7 is a view taken through Figure 1 on the line 7—7.

Referring more particularly to the drawings, the mounting, constructed in accordance with the practice of the invention and designated by 30 20, comprises a main frame 21, a pair of columns 22 supported by the main frame and wheels 23 and 24 to support the mounting.

In order to prevent unauthorized shifting of the mounting from a desired position the main frame is provided with a series of bearings 18 to accommodate pins 19 which engage the surface of the material supporting the mounting. Preferably a shaft 17 is secured to the mounting adjacent the wheel 24 to provide a grip member 40 which the operator may grasp for moving the mounting from one drilling site to another.

The main frame 21 is of substantially U-shape of which the side members 25 are arranged in parallelism and serve as supports for bearings 26 on the lowermost end of the columns 22. The bearings 26 are slidable along the members 25 and are provided with clamping plates 27 and bolts 28 whereby they may be clamped to the members 25.

The columns 22 are preferably disposed perpendicular to the main frame and serve as guides for bearings 29 on the ends of a hollow tool supporting member or bar 30 which is preferably of U-shape and the intermediate portion 31 of which 55 serves as a pivot for a guide frame 32 support-

ing a rock drill 33, the guide frame 32 being provided with clamping mechanism 34 which grips a cone 16 carried by the guide frame for clamping it to the bar 30, as is more particularly illustrated in Figure 2.

The clamping mechanism may be of well known type comprising a pair of grip members 15 and 14 to engage the cone 16. The members 15 and 14 are pivotally connected together, as by a pin 13, and the pressure employed for clamping the members 15 and 14 to the cone 16 may be applied by a nut 12 acting against the member 14 and threaded on a bolt 11 anchored to the member 15 and extending through said member 14. In the side of the member 15 is a partly-cylindrical recess 10 to receive the bar 30, and a yoke 9 actuated by nuts 8 threaded on bolts 7 and which bolts may be carried by the member 15 serves to secure the clamping device 34 to the bar 30.

In the bearings 29 are apertures 35 to slidably receive the columns 22, and adjacent the bearings 29 are clamps 36 of which the inner surfaces 37 conform to the contour of the columns 22. The clamps are pivoted at one end, as by a pin 38, to the bearings 29, and in the opposite ends of the clamps are slots 39 to receive eye-bolts 40 pivotally mounted on pins 41 seated in the bearings 29. The eye-bolts carry nuts 42 for forcing the clamps 36 into firm gripping engagement with the columns 22 to hold the bar 30 fixedly in position on the columns.

In order that the bar 30 may be readily lowered and raised on the columns 22 to enable the rock drill to be placed in an inclined position, as illustrated in Figure 4, or in a vertical position, as shown in Figure 1, the mounting is provided with an actuating device of which an example is more particularly illustrated in Figure 1 and shown as comprising a pair of drums 43 and 44 keyed to a shaft 45 journaled in the bar 30. Interposed between the drums 43 and 44, and keyed to the shaft 45, is a worm wheel 46 meshing with a worm 47 having shaft portions 48 and 49 seated in the bar 30. The shaft 49 extends exteriorly of the bar 30 and carries a crank 50 whereby the worm 47 and thus the drums 43 and 44 may be rotated.

Extending through the bar 30 and trained over guide rollers 51 within the member 30 is a flexible member, as for example a cable 52, which is wound upon the drum 43 and an end is anchored to a take-up device shown as an eye-bolt 53 which extends through a bracket 54 mounted upon a column 22. A nut 55 threaded

on the bolt 53 and seating upon the upper surface of the bracket 54 serves to adjust the bolt 53 to maintain the correct tension on the cable 52.

To the end that both bearings 29 may be shifted along the columns 22 with a minimum degree of friction between their cooperating surfaces a cable 56 wound upon the drum 44 is anchored to an eye-bolt 53 supported by the other column 22, and adjustment of the eye-bolt is effected in the manner of that connected to the cable 52.

The guide frame 32 and the rock drill 33 may be of conventional construction, it being understood that the rock drill 33 is slidably interlocked with the guide frame so that it may readily be moved toward the work or retracted therefrom. Such movement of the rock drill with respect to the guide frame may be effected by any suitable actuating device, as for example a drum 57 and a cable 58 of which an end is secured to the rock drill 33.

In operation, whenever it is desired to drill vertical holes the tool supporting member 30 is raised, by means of the drums and cables, along the columns 22 until the guide frame 32 may be placed in a vertical position. The clamps 36 are then firmly clamped to the columns 22 and will support the weights of the bar 30 and the elements carried by the bar. The rock drill 33 may then be set in operation and will descend along the guide frame 32 in accordance with the penetration of the working implement into the rock.

When used for drilling vertical holes the columns occupy positions closely adjacent the wheels 23 in order that the holes may be drilled closely to a vertical rock face. Should it be desired, however, to drill inclined holes into the base of a ledge the plates 27 are loosened and the columns 22 are moved along the members 25 in the direction of the wheel 24 and again clamped securely to the members 25. The clamps 36 are then loosened to permit free movement of the bearings 29 on the columns 22 and the drums 43 and 44 are rotated to lower the tool supporting member 30 and the guide frame 32 may then be inclined to the desired position.

After the guide frame and the rock drill have been correctly positioned the clamping devices 36 and 34 are again tightened to render the entire device rigid for a subsequent drilling operation.

I claim:

1. A mounting for rock drills, comprising a frame, columns on the frame, a tool supporting member slidable on the columns, flexible means on the columns and in the tool supporting member, means for connecting each extremity of the flexible means to the mounting, means within the tool supporting member to guide the flexible means and seat upon an intermediate portion thereof, guide means on the tool supporting member adapted to guide longitudinal movement of the rock drill with respect to said member, a drum for winding in any paying out the flexible means to raise and lower the tool supporting member, and means carried by the tool supporting member for clamping said member to the columns.

2. A mounting for rock drills, comprising a frame, columns on the frame and being slidable

thereon, a tool supporting member, bearings on the tool supporting member slidable on the column, flexible members on the columns having portions thereof lying within the tool supporting members, means in the tool supporting member to guide the flexible means, a drum in the tool supporting member to wind in and pay out the flexible means for raising and lowering the tool supporting member, and a take-up device for the flexible means.

3. A mounting for rock drills comprising a frame, a pair of columns slidable on the frame, a tubular tool supporting member, bearings on said member slidable on the columns, a cable passing through said tubular member to support said member, an adjustable take up device on the upper end of each column to secure each end of the cable to a column, guide means on the tool supporting member to guide longitudinal movement of the rock drill with respect to said member, and a drum for the cable on the tool supporting member to raise and lower the tool supporting member.

4. A mounting for rock drills comprising a frame, a pair of columns slidable on the frame, a tubular tool supporting member, bearings on said member slidable on the columns, a cable passing through said tubular member to support said member, an adjustable take up device on the upper end of each column to secure each end of the cable to a column, guide means on the tool supporting member to guide longitudinal movement of the rock drill with respect to said member, a drum for the cable on the tool supporting member to raise and lower the tool supporting member, and a second drum and cable to move the rock drill longitudinal with respect to said tubular tool supporting member.

5. A mounting for rock drills comprising a frame, columns on the frame and being slidable thereon, means to clamp the columns on the frame at any desired position, a tubular supporting member, bearings on the tool supporting member slidable on the columns, a cable passing through the supporting member to support said member, means to guide the cable in the tool supporting member, means at each end of the cable to secure an end thereof to each column, means to guide longitudinal movement of the tool with respect to the tool supporting member, and means to enable the cable to raise and lower the tool supporting member.

6. A mounting for rock drills comprising a frame, columns on the frame and being slidable thereon, means to clamp the columns on the frame at any desired position, a tubular supporting member, bearings on the tool supporting member slidable on the columns, a cable passing through the supporting member to support same member, means to guide the cable in the tool supporting member, means at each end of the cable to secure an end thereof to each column, means to guide longitudinal movement of the tool with respect to the tool supporting member, means to enable the cable to raise and lower the tool supporting member, and means to move the tool with respect to the tool supporting member.

DUDLEY W. HART.
